UNITED STATES PATENT OFFICE.

ELMER JOE GOODDING, OF CAMANCHE, CALIFORNIA.

WATER WHEEL.

Application filed March 1, 1924. Serial No. 696,230.

To all whom it may concern:

Be it known that I, ELMER J. GOODDING, a citizen of the United States, residing at Camanche, in the county of Calaveras, State 5 of California, have invented certain new and useful Improvements in Water Wheels, of which the following is a specification.

This invention relates to water wheels, especially adapted for use in small streams.

10 Briefly stated, an important object of this invention is to provide a water wheel which may be advantageously employed in streams where the level of the water rises and falls at different times of the year.

15 A further object of the invention is to provide a water wheel having simple means whereby the blades on return movement are positioned within the drum so that in case the water is flowing over the drum the return 20 blades will not be engaged by the water.

A further object of the invention is to provide a water wheel of the character specified which is of highly simplified construction, durable in use, and cheap to manufacture.

Other objects and advantages will be apparent during the course of the following description.

30 In the accompanying drawing, forming a part of this application, and in which like numerals are employed to designate like parts throughout the same:

Figure 1 is a perspective of the improved 35 water wheel in use.

Figure 2 is a vertical transverse sectional view through the same, and

Figure 3 is a sectional view taken at right angles to Figure 2.

40 In the drawing, wherein for the purpose of illustration is shown a preferred embodiment of the invention, the numeral 5 designates a shaft rotatably carried by the bearing 6 on the upper end of a plurality of 45 spaced standards 7. Figure 3 illustrates that a plurality of blades 8 extend radially from the shaft 5 and are secured thereto by fastening devices 9 of any suitable type.

50 In carrying out the invention the blades 8 are positioned in a drum, generally designated by the numeral 10, and which has a peripheral wall 11 provided with spaced slots for the passage of the outer portions of the blades. With reference to Figure 2 55 it will be observed that the outer portions of the blades pass between rollers 12 extend-

ing transversely of the drum and designed to reduce friction between the blades and the drum and to permit of the free radial movement of the several blades as will be 60 hereinafter fully pointed out.

The drum is provided with one closed end wall 15 having an axially arranged stub shaft 16 extended through a bearing 17 on a standard 18, while the opposite end wall 65 has a large central circular opening through which the shaft 5 extends into the drum, and which supports the blades therein, the inner end of shaft 5 being spaced from wall 15. The axis of the shaft 16 of the drum 70 is offset or in spaced parallel relation to the axis of the shaft 5 and consequently as the blades move toward the underside of the drum the outer portions of the same are extended through the drum and arranged in 75 the path of travel of the water. The drum rotates about a fixed axis and the shaft 5 carrying the blades rotates about a fixed axis, but notwithstanding this, the outer portions of the blades are gradually moved 80 through the peripheral wall 11 of the drum so that the same are presented to the flowing water in the stream.

As the blades move out of contact with the water, they are gradually returned to 85 the space within the drum and in case the water is flowing over the drum at a time when the water in the stream is high, the returning blades will not be forced to move 90 against the force of the water.

In operation, a sprocket wheel or gear 20 is connected to one end of the shaft 5 and the power generated by the wheel is transmitted by a sprocket chain, a series of gears, or the like, to a suitable point of use. 95

With reference to the foregoing description, taken in connection with the accompanying drawing, it will be seen that a water wheel constructed in accordance with this invention may be economically employed in small streams where the level of the water varies with the season. Owing to the highly simplified nature of the invention, the wheel will not easily get out of 100 repair and requires practically no attention.

I claim:

A water wheel assembly comprising a pair of spaced apart standards of unequal height adapted to be rigidly anchored in a flowing stream, horizontal bearings at the upper ends of said standards, a cylindrical 110

drum mounted between said standards, said drum having one end wall closed, a stub shaft rigidly associated with said wall and rotatably mounted in the bearing of the longer standard, the opposite end wall of said drum having a relatively large central opening, a second shaft rotatably mounted in the shorter of said standards, and extending through said open end wall into said drum, the peripheral wall of said drum

provided with transverse slots, a plurality of blades connected to said last named shaft extending radially therefrom and adapted for passage through said slots, the axes of the two shafts being offset in parallel relation, whereby the blades are reciprocated through the periphery of the drum by the rotation thereof. 15

ELMER JOE GOODING.
